TOOTHBRUSH

Irving Rosenwasser, Brooklyn, N. Y., assignor to
Nettie Rosenwasser, New York, N. Y.

Application April 26, 1941, Serial No. 390,493

2 Claims. (Cl. 15—143)

This invention relates to a tooth brush and more particularly pertains to the construction of the handle thereof.

Some of the distinguishing features and advantages of the invention are as follows: Enables the user of the brush to get a more natural and firmer grip so that the tooth-brush may be manipulated in any position with the advantage of such grip. It prevents the thumb and index finger of the user's hand from slipping forward when the brush is held and in use so that the brush may be effectually employed in brushing the teeth and massaging the gums of both the upper and lower arches. The brush when not in use may be deposited and held in a suitable or the common and conventional holder or receptacle and the bristles remain elevated above the surface of the holder so that none of the bristles come in contact with such surface. By avoiding such contact there is eliminated entirely the common condition of the bristles resting in and upon such matter as may and usually does settle and form on the surface of the holder or receptacle. This elimination leaves the brush and especially the bristles in a more sanitary condition. The resting position of the brush also permits the bristles to drain more quickly and to dry more thoroughly and completely. It also prevents the distorting or bunching of the bristles and reduces the possibility of the same decaying. The wear upon the bristles is also lessened. These mentioned features and advantages in turn result in prolonging the life and usefulness of the brush.

In the accompanying drawing—

Fig. 1 is a side view of a brush embodying the features of the invention;

Fig. 2 is a back view;

Fig. 3 is a side view of the brush and in dotted lines is shown the index finger resting in the arcuate surface of the upper abutment of the handle and the thumb resting in the arcuate surface of the lower abutment while the handle is gripped in a manner to enable the user to conveniently and effectively brush certain areas of the teeth and massage certain areas of the gums in both the upper and lower arches.

Fig. 4 is a view similar to Fig. 3 but showing the index finger resting in the arcuate surface of the lower abutment of the handle and the thumb resting in the upper abutment of the handle while the handle is gripped in a manner to enable the user to conveniently and effectively brush the remaining areas of the teeth and massage the remaining areas of the gums in both the upper and lower arches.

Fig. 5 is a side view of the brush and a portion of a conventional holder shown in section, the handle of the brush being disposed in a holder opening with the head of the brush and the bristles elevated in an upright position above the surface of the holder.

In accordance with the invention use is made of an element of any suitable material to provide a head 10 and a handle 11 in continuation with said head. The head has secured thereto cleaning or brushing means such as the bristles 12 shown. The handle at its juncture 13 with the head has raised portions 14 and 15 integral therewith. These raised portions 14 and 15 are disposed on the back and bristle sides respectively. The portion 14 has a curved or arcuate surface 16 and the portion 15 has a curved or arcuate surface 17. The arcuate surfaces 16 and 17 merge into the relatively broad flat surfaces 20 of the handle and diverge in the direction of the head. The surface 16 is longer than the surface 17 and as a consequence the raised portions are offset with respect to each other or spaced axially with respect to the longitudinal axis of the handle.

The raised portions hereinabove described thicken the handle at two places and constitute guides as well as anti-slip means, abutments and/or stop means. The arcuate surface in each 30 of these raised portions, respectively constitutes a more natural resting place for the inner surface of the index finger and/or thumb thereby permitting a more natural and firmer grip upon the brush. In this connection the positions 14 and 15 serve as abutments and as guides and as rests for the index finger and thumb interchangeably and prevent such fingers from slipping forward while resting naturally within the respective arcuate surfaces and thereby enabling 40 the user to obtain a more natural and firmer grip upon the handle so that the brush may be guided and manipulated in any position for the convenient and effectual brushing of the teeth and massaging of the gums.

45 Furthermore, when the brush is not in use it may be arranged on a suitable holder in such position with relation thereto that the bristles will be held elevated as shown for instance in Fig. 5. In this figure a portion of a holder is 50 designated 18, and said portion has an opening 19 therein in which the handle is disposed. This brings the arcuate surfaces 16 and 17 in contact with the opposite walls of the opening by virtue of which the brush is retained upright with the 55 bristles standing entirely away from any part of

the holder. Consequently the bristles will not rest in, or come in contact with, any matter which may have been accumulated on the holder; the bristles when wet may drain more quickly and completely, and will dry more thoroughly without distorting or bunching; possible decay and wear of the bristles are both reduced and diminished; the brush remains in a more sanitary condition until again required for use; and the life and usefulness of the brush is prolonged.

I claim:

1. A tooth brush having a handle in connection with the bristle-carrying-head of the brush, said handle having on the back or upper surface and the bottom or lower surface respectively two raised portions, the raised portion on the back

or upper surface of said handle being nearer the bristle-carrying-head than the raised portion on the bottom or lower surface of said handle and said raised portions serving as abutments for the purposes specified.

2. In a tooth brush, an element providing a bristle-head and a handle in continuation of said bristle-head, said handle having at its juncture with said bristle-head a raised portion with an arcuate surface both on the upper and lower surfaces of said handle merging into the flat surface portions thereof and said raised portions being offset with respect to each other axially of the longitudinal axis of the handle to serve as abutments for the purposes specified.

IRVING ROSENWASSER.
